UNITED STATES PATENT OFFICE

161,409

COMBINED PHOTOGRAPHIC CAMERA AND COVER THEREFOR

Arturo Bachi, Turin, Italy

Application December 8, 1948, Serial No. 150,043

Term of patent 7 years

(Cl. D61—1)

To all whom it may concern:

Be it known that I, Arturo Bachi, a citizen of the Republic of Italy, residing at Turin, in the Republic of Italy, have invented a new, original, and ornamental Design for a Combined Photographic Camera and Cover Therefor, of which the following is a specification, reference being had to the accompanying drawing, forming part thereof.

Fig. 1 is a front perspective view of a combined photographic camera and cover therefor, showing my new design with the cover open.

Fig. 2 of the drawing is a rear perspective view of the combined photographic camera and cover therefor of Fig. 1 with the cover closed.

I claim:

The ornamental design for a combined photographic camera and cover therefor, as shown.

ARTURO BACHI.
